CLAIM

The ornamental design for a set top television converter, as shown and described.

DESCRIPTION

FIG. 1 is a front, top and right side perspective view of the set top television converter showing our new design;

FIG. 2 is a top plan view of the converter;

FIG. 3 is a front elevational view of the converter;

FIG. 4 is a right side elevational view of the converter;

FIG. 5 is a left side elevational view of the converter;

FIG. 6 is a rear elevational view of the converter; and,

FIG. 7 is a bottom plan view of the converter.

The broken line showing of a cord in FIGS. 1, 2, and 4 –7 and of a panel in FIG. 6 is for illustrative purposes only and forms no part of the claimed design.
